(57) **CLAIM**

The ornamental design for a fetal doppler as shown and described.

DESCRIPTION

FIG. 1 is a front, left and top perspective view of a fetal doppler, showing my design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is another front, left and top perspective view of the fetal doppler in an alternate state.

The broken lines depict portions of the fetal doppler that form no part of the claimed design.

1 Claim, 9 Drawing Sheets
